THREAD GUIDE

Michael J. McHale, Scranton, Pa.

Application August 31, 1934, Serial No. 742,341

10 Claims. (Cl. 242—157)

My invention relates to thread guides for winding machines and more particularly to means for attaching a guide eye to a tension arm.

In application, Serial No. 708,480, filed January 26, 1934, now Patent No. 1,965,044, issued July 3, 1934, I have disclosed a thread guide fastening means in combination with a faller arm structure, wherein the guide may be easily and quickly replaced without the use of any special tool. The present invention is an improvement over the arrangement disclosed in the above referred to application and relates to an improved thread guide structure of general application with winding machines and various attachments used therewith.

It is the purpose of the present invention to provide a thread guide fastening means wherein the guide may be easily and quickly replaced without the use of any special tool or instrument.

The conventional tension arm used in connection with the faller arm structure may be used with slight modification, and the thread guide structure is constructed and arranged so that it will not become loose due to vibration or other causes.

An object of my invention is to provide a fastening means for thread guides whereby the guide eye may be readily attached or detached from its supporting arm or bracket.

Another object of my invention is to provide an improved locking means for the guide whereby the guide is held in tight engagement with the support.

Still another object of my invention is to provide an improved thread guide eye adapted to be used in combination with various types of winding machine structures and attachments used therewith.

With these and other objects in view, which may be incident to my improvements, the invention consists in the parts and combinations to be hereinafter set forth and claimed, with the understanding that the several necessary elements, comprising my invention, may be varied in construction, proportions and arrangement, without departing from the spirit and scope of the appended claims.

In order to make my invention more clearly understood, I have shown in the accompanying drawing means for carrying the same into practical effect, without limiting the improvements in their useful applications to the particular constructions, which for the purpose of explanation, have been made the subject of illustration.

In the drawing:

Figure 1 is a perspective view showing the im-

proved thread guide structure attached to a faller arm.

Fig. 2 is a perspective view of the upper portion of a tension arm and the thread guide, showing the relative position of the parts before the guide is mounted.

Fig. 3 is a front view of the arrangement shown in Figure 1; and

Fig. 4 is a perspective view of a horizontal tension arm and a modified form of thread guide showing the relative position of the parts before the guide is mounted upon the tension arm.

Referring to the drawing and more particularly to Figure 1, there is shown a conventional faller arm 1 adapted to be pivotally mounted at 2 and 15 having a tension arm 3 attached thereto by means of a set screw 4. The free end of the tension arm is formed with a looped portion comprising upper and lower sections 5 and 6 respectively. It will be noted that the upper section 5 20 is horizontal and terminates in a free end 7. The lower section 6 is bent inwardly from a point 8 near the upper end of the wire, forming a contracted portion at the entrance to the loop. The purpose of this arrangement is to provide a 25 spring action between the sections, so that the guide eye will be securely held in the operative position as will be hereinafter more fully described.

Mounted upon the looped portion of the tension arm is a guide eye designated generally by numeral 9. The guide eye comprises a body portion 10 formed with a thread receiving opening 11 and a longitudinal recess 12 forming a seat for the horizontal section 5. As more clearly 35 shown in Figure 2 the body portion of the guide eye is tapered at the end opposite the thread receiving opening and is formed with grooves 13 and 14, either of the grooves forming a seat for the lower section 6 when the guide is attached 40 to the tension arm.

In attaching a guide to the tension arm, assuming the parts are in the position shown in Figure 2, the upper section 5 of the tension arm is inserted into the longitudinal recess 12 formed 45 in the body portion of the guide and the bent-over portion 8 is moved to the entrance of groove 14. The horizontal section 5 is then pushed forwardly into recess 12, a portion of the lower section 6 seating in the groove 14. The grooves 13 and 14 are substantially flat from the entrance to the grooves to a point near the end of the tapered portion of the body of the guide. When the guide is placed upon the tension wire, 55

due to the contracted portion near the entrance to the loop, section 5 is moved upwardly and lower section 6 assumes a substantially horizontal position so that in the final movement 5 of the guide inwardly, the lower section 6 of the loop seats with a snap action to securely hold the guide in position on the tension arm. Grooves 13 and 14 not only function as a seat for a portion of the lower looped section, but also prevent tilting or rolling of the guide after it is seated on the end of the tension arm.

Referring to Figure 4, I have shown a modified form of guide eye and horizontal support member. In this arrangement, the guide eye, designated generally by numeral 15, is supported 15 on a horizontal tension arm 16 adapted to be attached to the side frame of a winding machine. The tension arm 16 is formed with a double looped portion comprising a lower section 17, an upper section 18 and an intermediate section 19. It will be noted that the lower and upper sections 17 and 18 are parallel and that the intermediate section 19 is bent inwardly from a point 20 towards the lower section 17.

25 The guide eye 15 used with the horizontal tension arm, comprises a body portion 21 formed with a thread receiving opening 22, a longitudinal recess 23 and grooves 24 and 25 formed in the end of the guide opposite the thread receiving opening. In attaching the guide to the support arm, upper section 18 is inserted into the horizontal recess 23 and the intermediate section 19 is adapted to slide into one of the grooves 24 or 25. Due to the configuration of the looped portion, a spring action is obtained between the sections of the loop, whereby the intermediate section 19 snaps into position in the groove when the guide is pushed onto section 18 with the free end of the section at its innermost position within the groove 23.

40 It will now be appreciated that I have provided an improved guide eye which may be readily and easily attached to its support member. The guides will fit either form of support disclosed herein and the provision of double grooves in the body portion of the guides facilitates mounting of the eyes, for the reason that it is not necessary that the guides be placed in one certain position before they can be attached to a tension arm. It will be further noted that in this arrangement the eye may be reversed so that the thread receiving opening is either to the right or left of the tension arm.

45 While I have shown and described the preferred embodiment of my invention, I wish it to be understood that I do not confine myself to the precise details of construction herein set forth, by way of illustrations, as it is apparent that many changes and variations may be made 50 therein, by those skilled in the art, without departing from the spirit of the invention, or exceeding the scope of the appended claims.

In the claims:

1. In a thread guide device for winding machines, the combination of a tension wire having a support engaging section and an arm extending outwardly therefrom, the free end of the arm terminating in a looped portion adapted to receive a guide eye, said looped portion comprising upper and lower substantially parallel sections, the upper section terminating in a free end, a guide eye attached to the looped portion, comprising a base portion and a thread receiving portion, a recess longitudinally of the base portion forming a seat for the free end of

the loop and a groove to receive a portion of the lower horizontal section of the loop.

2. In a thread guide device for winding machines, the combination of a tension wire having a central support engaging section and an arm extending outwardly therefrom, the free end of the arm terminating in a looped portion adapted to receive a guide eye, said looped portion comprising upper and lower substantially parallel sections, a guide eye attached to the looped portion, comprising a tapered body portion having a thread receiving opening, a recess longitudinally of the body forming a seat for the free end of the loop and a groove in the tapered portion of the body to receive a portion of the lower horizontal section of the loop.

3. In a thread guide device for winding machines, the combination of a tension wire having a central support engaging section and an arm extending outwardly therefrom, the free end of the arm terminating in a looped portion adapted to receive a guide eye, said looped portion comprising upper and lower substantially parallel sections, a guide eye attached to the looped portion, comprising a body portion having a thread receiving opening, the end of the guide opposite the thread receiving opening being tapered, a recess longitudinally of the body forming a seat for the free end of the loop, and two parallel grooves formed in the tapered end of the body portion, either of said grooves being adapted to receive a portion of the lower horizontal section of the loop.

4. In a thread guide device for winding machines, the combination of a tension wire having a central support engaging section and an arm extending outwardly therefrom, the free end of the arm terminating in a looped portion adapted to receive a guide eye, said looped portion comprising upper and lower sections, the upper section being horizontal and terminating in a free end, a guide eye attached to the looped portion, comprising a tapered body having a thread receiving opening, a recess longitudinally of the body forming a seat for the free end of the loop and a groove in the tapered portion of the body to receive a portion of the lower section of the loop.

5. In a thread guide device for winding machines, the combination of a tension wire having a central support engaging section and an arm extending outwardly therefrom, the free end of the arm terminating in a looped portion adapted to receive a guide eye, said looped portion comprising upper and lower sections, the lower section being bent inwardly toward said upper section, a guide eye attached to the looped portion comprising a tapered body portion having a thread receiving opening, a recess longitudinally of the body forming a seat for the free end of the loop, and a groove in the tapered portion of the body to receive a portion of the lower section of the loop.

6. In a thread guide device for winding machines, the combination of a tension wire having a central support engaging section and an arm extending outwardly therefrom, the free end of the arm terminating in a looped portion adapted to receive a guide eye, said looped portion comprising upper and lower sections, the upper section being horizontal and terminating in a free end, the lower section being bent inwardly toward said upper section, a guide eye attached to the looped portion, comprising a tapered body

having a thread receiving opening, a recess longitudinally of the body forming a seat for the free end of the loop and a groove in the tapered portion of the body to receive a portion of the lower section of the loop.

- 5 7. In a thread guide device for winding machines, the combination of a tension wire having a support engaging section and an arm extending outwardly therefrom, the free end of the arm 10 terminating in a double looped portion adapted to receive a guide eye, said looped portion comprising three substantially parallel sections, the upper section terminating in a free end, a guide eye attached to the looped portion comprising a base portion and a thread receiving portion, a recess longitudinally of the base portion forming a seat for the free end of the loop and a groove 15 to receive a portion of the intermediate section of said looped portion.
- 20 8. In a thread guide device for winding machines, the combination of a tension wire having a support engaging section and an arm extending outwardly therefrom, the free end of the arm 25 terminating in a double looped portion adapted to receive a guide eye, said looped portion comprising upper and lower horizontal sections and an intermediate section bent inwardly towards said lower section, the upper horizontal section terminating in a free end, a guide eye attached 30 to the looped portion comprising a base portion and a thread receiving portion, a recess longitudinally of the base portion forming a seat for the free end of the loop and a groove to receive

a portion of the intermediate section of said looped portion.

9. In a thread guide device for winding machines, the combination of a tension wire having a support engaging section and an arm extending outwardly therefrom, 5 a guide eye comprising a base portion having a recess extending longitudinally thereof and a thread receiving portion, means to attach the guide to the arm comprising a looped member having upper and lower sections, the upper section terminating in a free end, 10 said looped member being formed with a contracted portion whereby the guide eye is clamped between the sections of the loop when the free end of the upper section is seated in the longitudinal recess in the base portion of the guide. 15

10. In a thread guide device for winding machines, the combination of a tension wire having a support engaging section and an arm extending outwardly therefrom, the free end of the arm 20 terminating in a looped member adapted to receive a guide eye, said looped member comprising upper and lower sections formed with a restricted portion, a guide eye attached to the looped member comprising a body portion and a thread 25 receiving portion, a recess in the body portion forming a seat for the free end of the loop and a groove in the body to receive a portion of the lower section of the loop whereby the guide eye is clamped between the sections when the free 30 end of the upper section is seated in the recess in the body of the guide.
